UNITED STATES PATENT OFFICE.

WINSLOW P. EAYRS, OF HUDSON, NEW HAMPSHIRE, ASSIGNOR OF ONE-THIRD TO MICHAEL R. PERKINS AND ONE-THIRD TO HOWE CALL, OF PORTSMOUTH, NEW HAMPSHIRE.

CARBON PRODUCT AND METHOD OF MAKING SAME.

No. 829,464.

Specification of Letters Patent.

Patented Aug. 28, 1906.

Application filed November 1, 1905. Serial No. 285,398.

To all whom it may concern:

Be it known that I, WINSLOW P. EAYRS, of Hudson, in the county of Hillsboro and State of New Hampshire, have invented certain new and useful Improvements in Carbon Products and Methods of Making the Same, of which the following is a specification.

My invention relates to such carbon products as brushes and contacts adapted for electrical purposes. It aims to provide an effective composition for and method of making and producing therefrom the desired articles.

The drawing illustrates a brush made in accordance with my invention.

My improved composition consists of finely-reduced carbon freed from gritty or vitreous constituents which may be present in the crude element and with which is mixed reduced soapstone similarly separated and some such binder or adhesive solution as rice-water. The proportions of the first two ingredients are such as to give the desired conductivity and freedom from friction, the latter being most essential if the composition is to be used for brushes contacting with the commutators of electrical apparatus and in similar connections. A sufficient amount of rice-water is added to secure a paste of the proper consistency for molding.

In making articles from this composition I first deliver the crude carbon to a pulverizing-machine of any suitable type, but preferably to one in which the material is subjected to the action of a gaseous fluid—for example, a current of air created by the pulverizing agencies. As the carbon is reduced the finer purer portion rises by virtue of its lesser gravity and settles outside the pulverizing-receptacle on a suitable surface from which it may be readily collected. The coarser heavier impurities remain in the pulverizer for removal when desired. Soapstone is similarly reduced and separated and the finer portion mixed with an amount of carbon and the rice-water, determined, as previously stated, to furnish a paste. This is then molded or pressed in the customary way.

When the article produced—for example, the brush A—requires it, it may be coated, in whole or in part, as is indicated at *a*, by plating with copper by electrodeposition. The covering thus formed adheres firmly to the article and insures perfect contact between it and its holder.

By my improved process a product is secured at a minimum cost which is free from abrasive particles, which operates smoothly under frictional contact, and which is dense and resistive of fracture.

Having thus explained the nature of my invention, I claim—

1. The method of making articles of carbon, which consists in pulverizing the carbon, subjecting it to the action of a fluid current to separate the lighter portion, mixing this lighter portion with rice-water, and molding the mixture into the desired form.

2. The method of making articles of carbon, which consists in pulverizing the carbon and soapstone, subjecting each to the action of a fluid current to separate the lighter portions, mixing said lighter portions with an adhesive, and molding the mixture into the desired form.

3. The method of making articles of carbon, which consists in pulverizing carbon and soapstone, subjecting each to the action of a fluid current to separate the lighter portions, mixing said lighter portions with rice-water, and molding the mixture into the desired form.

4. The herein-described composition, consisting of reduced carbon and soapstone.

5. The herein-described composition, consisting of reduced carbon and rice-water.

6. The herein-described composition, consisting of reduced carbon, soapstone, and rice-water.

In testimony whereof I have affixed my signature in presence of two witnesses.

WINSLOW P. EAYRS.
